US0D1021092S

(12) **United States Design Patent** (10) **Patent No.:** **US D1,021,092 S**
(45) **Date of Patent:** **** Apr. 2, 2024**

(54) **SURGICAL SAW BLADE**

(71) Applicant: **DePuy Synthes Products, Inc.**,
Raynham, MA (US)

(72) Inventor: **Stefan Gisler**, Oberdorf (CH)

(73) Assignee: **DEPUY SYNTHERS PRODUCTS,
INC.**, Raynham, MA (US)

(**) Term: **15 Years**

(21) Appl. No.: **29/865,419**

(22) Filed: **Jul. 25, 2022**

Related U.S. Application Data

(63) Continuation of application No. 16/657,524, filed on Oct. 18, 2019, now Pat. No. 11,490,898.

(57) **CLAIM**

The ornamental design for a surgical saw blade, as shown and described.

DESCRIPTION

FIG. 1 is a top, front, and left perspective view of a surgical saw blade in accordance with my new design;

FIG. 2 is a top plan view of the embodiment of FIG. 1;

FIG. 3 is a bottom plan view of the embodiment of FIG. 1;

FIG. 4 is a front end elevational view of the embodiment of FIG. 1;

FIG. 5 is a rear end elevational view of the embodiment of FIG. 1;

FIG. 6 is a left side elevational view of the embodiment of FIG. 1; and,

FIG. 7 is a right side elevational view of the embodiment of FIG. 1.

The broken lines shown in FIGS. 1-7 illustrate portions of the surgical saw blade that form no part of the claimed design.

1 Claim, 3 Drawing Sheets
